OCCASIONAL CHAIR OR THE LIKE

John J. Keal, Los Angeles, Calif., assignor to Capitol Chair Company, Inc., Culver City, Calif.

Application April 12, 1955, Serial No. 35,473

Term of patent 7 years

(Cl. D15—1)

Fig. 1

I claim:

The ornamental design for an occasional chair or the like, substantially as shown.
